UNITED STATES PATENT OFFICE.

EUGENE B. WILLIAMS, OF BOSTON, MASSACHUSETTS, ASSIGNOR TO B. F. STURTEVANT COMPANY, OF BOSTON, MASSACHUSETTS, A CORPORATION OF MASSACHUSETTS.

CENTRIFUGAL FAN.

1,072,549.

Specification of Letters Patent. Patented Sept. 9, 1913.

Application filed December 6, 1909. Serial No. 531,430.

To all whom it may concern:

Be it known that I, EUGENE B. WILLIAMS, a citizen of the United States, residing at Boston, in the county of Suffolk and State 5 of Massachusetts, have invented certain new and useful Improvements in Centrifugal Fans; and I do hereby declare the following to be a full, clear, and exact description of the invention, such as will enable others skilled in the art to which it ap- 10 pertains to make and use the same.

The invention relates to centrifugal fans which take the air in axially and discharge it circumferentially of the fan wheel, and 15 more particularly to a fan of this character in which there is a free discharge of the air all about the periphery of the wheel, as distinguished from a fan in which the wheel is surrounded by a scroll casing having a tangential outlet for the air.

The object of the invention is to provide a fan of this character having a novel and improved construction and mode of operation whereby its efficiency in handling large 25 volumes of air and producing a high suction or pressure when operating at high speed is increased.

To this end the invention consists in the features of construction and combinations 30 hereinafter described and set forth in the claims.

The features of the invention will be readily understood from an inspection of the accompanying drawings, and the following 35 detailed description of the fan shown therein.

In the drawings Figure 1 is a front elevation of the fan embodying the invention, and Fig. 2 is a vertical section on line 40 2—2, Fig. 1.

As shown in the drawings, the wheel of the fan is provided with a central conical hub 1 which is secured to the shaft 2. A back plate 3 is secured to the rear side of 45 the hub 1, and a series of fan blades 4 are secured in any suitable manner to the back plate and hub. The blades 4 are comparatively narrow axially, and extend from the circumference of the wheel substantially in 50 to the shaft on which the wheel is supported, since it has been found that this form of blade increases the efficiency of the fan. The front edges of the blades are preferably in- clined toward the rear of the fan, so that 55 the blade area is less near the axis of the

fan than it is at the periphery of the inlet eye. This also adds to the efficiency of the fan, since there is less air entering and passing along the blades at the axis of the fan than there is toward its circumference. 60 The air enters the wheel through an eye 5, and the flange or plate 6 forming the eye is frusto-conical in shape, so that a tapered or conical inlet guide is formed about the eye. This conical inlet eye receives the inflowing 65 air and guides it axially through the eye in an efficient manner.

On the rearwardly inclined front edges of the blades 4 is a ring 9 which connects the front edges of the blades together, said ring extending inwardly in parallel relation with the inwardly converging portion of the plate 8. The ring 9 together with the back plate 3 from a contracted throat at the discharge end of each fan section which directs the air along the converging faces of the plates 7 and 8 in an outward direction and free from cross currents or eddies. The air entering the fan wheel is carried around by the blades, and is thrown off circumferentially from the fan wheel about the circumference of the fan. The flow of the air off the ends of the blades is in a general tangential direction, the angle which the currents of air make with the tangent at the point of discharge depending upon the shape of the blades. In order that this angle may be increased, the blades are curved rearwardly toward their outer ends. Since the air is thrown outwardly about the periphery of the fan wheel with a certain force and velocity against the pressure of the surrounding air, the efficiency of the fan will be increased by increasing the radial component of the force tending to carry the air 90 away from the periphery of the fan. I have found that the efficiency of a fan of this character is greatly increased by arranging stationary guides on opposite sides 95 of the fan wheel between which the air thrown off by the wheel is directed out into the surrounding atmosphere. To secure the best results, these stationary guide plates should converge toward their outer edges, so that the circumferential area between the two blades is substantially the same, whatever the distance from the axis of the wheel. These stationary plates probably add to the efficiency of the fan by offering a frictional 100 resistance to the circumferential movement 105 110

of the air, so that they operate to change the direction of the flow of the air and render it more nearly radial to the wheel. The air is therefore discharged from between the 5 plates more directly against the inward pressure of the surrounding atmosphere, with a resulting decrease in the power required to drive the wheel, and an increase in the efficiency of the wheel and in the volume 10 of air handled by it.

As shown, the stationary guide plates between which the air is discharged consist of a disk 7 arranged back of the fan wheel, and a frusto-conical plate 8 connected with the 15 guide plate 6, and arranged at the front of the wheel. These plates converge toward their outer edges, so that the area of the discharge passage between the plates remains substantially constant. These plates 20 may be supported in fixed position with relation to the fan wheel in any manner best suited to the conditions under which the fan is to be used.

While it is preferred to employ the specific construction and arrangement shown and described, it will be understood that this construction and arrangement is not essential except so far as specified in the 25 claims, and may be varied or modified without departing from the invention.

Having explained the nature and object of the invention, and specifically described one

form of fan in which it may be embodied, what I claim is:—

1. A centrifugal fan comprising a front 35 plate having a frusto-conical eye and an inwardly converging outer rim portion, a rear plate having an inwardly converging rim, a fan wheel between said plates and provided with radial blades having rearwardly inclined outer front edges, a circular plate on the rear of said blades, and a ring mounted on the inclined front edges of said blades and inclined in parallelism with the inwardly converging portion of the front 40 plate, substantially as set forth.

2. A centrifugal fan comprising front and rear plates having inwardly converging rim portions, the front plate provided with a frusto-conical eye, a fan wheel between 50 said plates, provided with radial blades having rearwardly inclined outer front edges, a circular plate on the rear of said blades, and a ring mounted on the inclined front edges of said blades and connecting said blades together and forming contracted throats at the discharge ends of each fan section adapted to discharge the air in line with the converging inner surface of the front plate, substantially as set forth.
